Primary Examiner—Cathron C. Brooks*Assistant Examiner*—Austin Murphy*(74) Attorney, Agent, or Firm*—Stuart M. Goldstein(57) **CLAIM**

The ornamental design for an obituary program binder, as shown and described.

DESCRIPTION

FIG. 1 shows an isometric view of the obituary program binder of the present invention with its binder partially opened.

FIG. 2 shows the front view of the obituary program binder of the present invention, the front and rear views being identical.

FIG. 3 shows a side view of the obituary program binder of the present invention.

FIG. 4 shows the opposite side view of the obituary program binder of the present invention.

FIG. 5 shows the bottom view of the obituary program binder of the present invention with the binder of the organizer in a closed position. The bottom and top views are identical when the binder is closed; and,

FIG. 6 shows the obituary program binder of the present invention with its binder fully opened and with one of its pages extended.
